UNITED STATES PATENT OFFICE.

HARRY H. GOLDSTEIN, OF HARTFORD, CONNECTICUT.

VENDING-MACHINE.

1,217,592.

Specification of Letters Patent. Patented Feb. 27, 1917.

Application filed November 4, 1915. Serial No. 59,564.

To all whom it may concern:

Be it known that I, HARRY H. GOLDSTEIN, a citizen of the United States, residing at Hartford, in the county of Hartford and 5 State of Connecticut, have invented a new and Improved Vending-Machine, of which the following is a specification.

My invention relates to the class of devices above mentioned, and an object of my 10 invention, among others, is to provide a durable and inexpensive device of this class, of simple construction, and one especially extremely effective for accomplishing its purpose.

15 One form of vending machine, embodying my invention, and in the construction and use of which the objects herein set out, as well as others, may be attained, is illustrated in the accompanying drawings, in which—

20 Figure 1 is a view in vertical section through the lower part of a vending machine embodying my invention.

Fig. 2 is a view in vertical section through a part of the lower portion of my improved 25 machine on plane denoted by dotted line 2—2 of Fig. 1.

Fig. 3 is a view in horizontal section through a portion of a lower part of the case, on a plane located just above the vending mechanism.

30 Fig. 4 is a detail view in vertical section through the lower part of my improved vending machine on a plane passing between the vending slides, and with parts broken 35 away to show construction, the vending slide being shown as pushed in.

Fig. 5 is a detail view illustrating the operation of the clearing lever.

A box or case of any desired shape and 40 composed of any suitable material is provided to inclose the mechanism of my improved vending machine, as herein shown this case comprising a base portion 7 containing the vending chamber, and a part 8 45 rising therefrom at the back and containing the goods chamber that is closed by a front plate 9 having recesses in each side edge at the bottom thereof to receive lugs 10 projecting inwardly from the side parts to hold 50 the bottom of the front piece in place. The vending chamber in the base is closed at the top by a cover 11 fitting grooves 12 in the side parts of the base and having a cover

retaining lip 13 at its rear edge and a front retaining lip 14 at its front edge, the former 55 to be located behind the lower end of the front plate 9 to hold the cover in place and the latter to be located in front of the top edge of the front piece 15 to retain it in place. A money receptacle or tray 16 is rigidly secured to the front piece 15, projecting 60 backwardly therefrom at its bottom edge, as shown in Fig. 1 of the drawings. This tray rests upon shoulders upon the side parts of the case to support the tray against vertical 65 displacement, in the construction herein shown, said tray having flanges 17 projecting laterally from opposite sides thereof to enter grooves 18 to retain the tray in position. When the top edge of the front plate 70 9 is secured, as by means of a lock, it will be seen that the parts above described, are fastened securely in place.

The vending mechanism is located on a supporting plate or base 19 having retaining 75 flanges 20 located in supporting plate grooves 21 in the side parts of the case. The plate is slid into place in the grooves 21, and projections 22 at the rear edge of the plate have plate retaining recesses 23 to receive 80 lugs 24 on opposite sides of the goods receptacle 25 and at the bottom thereof to lock the supporting plate against removal and to support said receptacle vertically, the latter being held against forward movement 85 by the front plate 9. A lip 26 from the bottom edge of the goods receptacle fits into the space between the projections 22, thus holding the goods receptacle from sidewise movement.

90 The supporting plate or base 19 has a series of slide openings 27 with depending flanges 28 on opposite sides of each opening and slide retaining lips 29 at the bottom edge of each flange to support vending 95 slides for reciprocating movement. These openings 27 are of uniform width throughout to receive and permit free and unrestricted movement of the vending slide to be hereinafter described. They are of substantial depth to form a supporting surface for said slides to insure their steady movement and without cramping. A push rod 30 is supported for sliding movement in an end plate 31 extending across the front edge 100 of the supporting plate or base, and upon

end or cross bar 32 and a cross bar 33 appurtenant to each slide opening. A spring-containing tube 34 has its ends secured in the wall 32 and bar 33 in each slide opening, 5 and a vending slide actuating spring 35 is located in this tube surrounding the push rod 30, one end of the spring thrusting against the bar 33 and the opposite end against a pin 49 that rests against a cross piece 36 of the vending slide. This tube 34 prevents the spring from becoming inoperative should it break and the tube extends through the cross piece 36 and has a fin 37 on its upper surface to prevent turning 10 movement of the tube and false or spurious objects, fraudulently introduced into the machine, from lodging upon the tube and thereby clogging the mechanism.

The vending slides are each composed of 20 a side 38 having cross pieces 36 and 51, a top piece 39, and a pusher 40 integral therewith, each slide also including a removable side piece 41 secured in place in any suitable manner to form an opening 42 25 through the vending slide. These sides are of considerable width and are wider at the bottom than at the top forming an open sided box like structure to inclose the coin operated mechanism and also an inclosed 30 passage through which slugs and other extraneous articles are conducted to the tray 16. The tapered shape of the sides enables the slide-ways for coins to be disposed in an inclined position so that spurious devices will move slowly enough to permit 35 complete action of a device for removing the spurious devices from the slideway. Coin shelves 43 extend along each side wall of the opening 42 in an inclined position to 40 constitute a slideway for a coin, the slides being normally positioned to locate these slideways underneath the coin slots 44 through the cover 11 of the case. A magnet 45 forms a part of one side wall of each 45 slideway that, from the top to the lower edge of the magnet, is of a width practically equal to that of a coin intended for use in the machine, but below the magnet is of a width so much greater than the diameter of 50 the coin that a fraudulent device, used in place of a coin may move off the shelf 43, this increase in width of the slideway being on the magnet side of said slideway, so that 55 the fraudulent device may move off the shelf of the slideway on the side opposite the magnet, and will do this when attracted by the magnet.

A clearing lever 46 is pivotally mounted, 60 preferably on the side wall of the opening 42, one edge of this lever being formed to constitute a portion of the coin shelf, on the magnet side of the slideway. An arm 47 of this lever has a slot to receive a clearing lever operating pin 48 extending from the side of the push rod 30, and the pin 49,

hereinbefore described as receiving the thrust of the spring also constitutes a guide that touches the edge of the tube 34 and prevents turning movement of the push rod sufficiently to disengage the pin 48 from the slot in the lever.

A cap plate 50 is located over the coin slideway opposite the magnet, this cap plate, in the arrangement shown herein, being secured to and projecting from that wall of the opening 42 opposite the magnet. As it appears in Fig. 1 the outer end of this cap plate is necessarily shown as unsupported, this in order to illustrate its position with respect to the slideway. In many instances the magnetic force of the magnet would be so great as to lift the edge of a device, susceptible to the magnetic influence, off from the shelf opposite the magnet and place such device flatwise across the arms of the magnet. The cap plate effectually prevents this action.

The cross piece 51 projects from the under side of the vending slide or pusher, and has an opening of a size to receive the push 90 rod 30 but of a width less than the diameter of a coin to be used in the device.

It will readily be seen that a coin inserted through one of the coin slots 44 will pass, by gravity, to the lower end of the coin 95 slideway and into the position shown in Fig. 1 where it rests upon the lips 29 at the forward end thereof. When the case is placed in a substantially level position the momentum of the coin will carry it past the 100 wide part of the slideway and retain it on the shelves throughout its entire movement. When it has reached the position shown in Fig. 1 pressure upon the push rod 30 will 105 move it against the tension of the spring against the coin, pushing the latter against the cross piece 51 and thus causing movement of the vending slide and the pusher 40 to crowd the bottom article in the goods chute out at the rear side of said chute from 110 which it falls into the delivery chute 52.

Frequently a device of about the size of a coin and composed of metal that will respond to the action of the magnet is employed for the purpose of fraudulently 115 obtaining goods from the machine. The momentum of such a fraudulent device will be sufficient to cause it to pass the magnet, the cap plate 50 preventing such a device from being lifted, and as this fraudulent 120 device reaches the lower edge of the magnet, the force of the latter will tend to draw the device quickly around such lower edge. This will draw the opposite edge of the device off from the shelf and its momentum aided 125 by the action of gravity will force it from the attraction of the magnet, and such device will, therefore, fall between the side parts of the vending slide and back of a stop 53 projecting upwardly from the cross 130

bar 33. Grooves are formed on opposite sides of this stop and extend down to the lips 29 in each vending slide and the side parts or box of each slide extend into these 5 grooves, as shown in Fig. 2. Upon striking the tube 34 the fin 37 thereon will cause the fraudulent device to fall into the money receptacle without lodgment in any place. An object in preventing such a device from being drawn upward across the arms of the magnet is that such position would cause continuous action of the magnet across its poles to its harm and furthermore upon removal of such fraudulent device from this 10 position its course would be less certain than in a case where it followed the path above described.

Should, however, such device be caught by the magnet, as the push rod 30 is moved 20 inward the action of the lever 46 would clear the device from the magnet.

It frequently happens that disks of paper or other light material are employed with fraudulent intent, and such articles falling 25 into the position of the coin upon the lips 29 would sometimes be so retained that repeated movements of the push rod 30 would result in repeated movement of the pusher 40 and therefore repeated ejection of goods 30 from the goods chute. To prevent such fraudulent use of the machine a pivoted trap 54 is mounted above each coin slideway, depending across such slideway, and this trap will be of such construction that weight 5 of a coin will be sufficient to remove it from the path of the coin and allow the latter to continue its course. This trap will be sufficient, however, in case of the use of a paper disk or disk of other light material to stop the movement of such disk along the coin slideway and the disk upon striking the trap will either be dislodged from the slideway and fall into the coin tray through the passage back of the stop 53 or will be held by the trap upon the coin slideway. In the latter event the operation of the push rod 30 and consequently of the clearing lever 46 will cause the paper disk to be dislodged and delivered into the coin receptacle through the passage above mentioned.

In order to insure the delivery of goods upon the deposit of each lawful token or coin, even though the vending slide may not be caused to move to its full extent, at the first or succeeding operation of the push rod, a pawl 55 is pivotally secured to the side of each vending slide, the lower end of the pawl engaging with a rack 56 to prevent backward movement of the slide. Should pressure upon the push rod be released before the slide has been moved sufficiently to insure delivery of an article from the goods receptacle, this pawl will prevent the vending slide from backward movement, but when said slide has been moved to an ex-

tent to insure the delivery of an article from the goods receptacle then the pawl will be disengaged from the rack and will present no obstruction to the backward movement of the vending slide.

A rider 57 is made to be carried on the pile 58 of goods in the receptacles 25, and a stop bolt 59 is carried in this rider in position to enter a hole 60 in the pusher 40 when the last package has been removed from said receptacle. This operation retains the vending slide at one limit of its play and causes the top 39 of the vending slide to close the coin slot 44.

While I have shown and described herein a satisfactory form of mechanism that embodies my ideas, this may be changed to a greater or lesser degree and yet be within the spirit and intent of the invention.

I claim—

1. A vending machine including a case having a coin slot, a vending slide having its lower portion spaced from the coin slot, side parts rising from said lower portion and of a width to provide an open sided box, said side parts having a slideway extending downwardly in a diagonal direction at the front edge of the opening to said box to guide the movements of a coin from said coin slot, a goods receptacle mounted in the case, a pusher mounted on the slide to remove goods from said receptacle, and means arranged to be connected with the slide to operate it by the interposition of a coin.

2. A vending machine including a case having a coin slot, a vending slide spaced from said coin slot and having an open sided box rising therefrom with an opening extending in the direction of depth therethrough, and a slideway formed in the side walls of said box at the edge of an opening therein and extending in a diagonal direction across said opening to guide the movements of a coin from said coin slot, a stop projecting upwardly within said opening, a goods receptacle mounted in the case, a pusher mounted on the slide to remove goods from said receptacle, and means arranged to be connected with the slide to operate it by the interposition of a coin.

3. A vending machine including a case having a coin slot, a supporting plate located within the case and having depending flanges forming a groove for a vending slide, a stop projecting upwardly between said flanges forming grooves, a vending slide comprising side parts with their lower edges located in said grooves, said side parts rising from the slide and having a slideway extending in a diagonal direction along the upper edge of the slide to guide the movements of a coin from the coin slot, a goods receptacle mounted in the case, a pusher mounted on the slide to remove goods from said receptacle, and means arranged to be

- connected with the slide to operate it by the interposition of a coin.
4. A vending machine including a case having a coin slot, a supporting plate located within the case and having depending flanges forming a slide opening of uniform width from bottom to top to receive a vending slide inserted therein from the top, a vending slide located within said opening and including side parts with a slideway to guide a coin from said coin slot, and means for operating the vending slide.
5. A vending machine including a case having a coin slot, a supporting plate located within the case and having depending flanges forming a slide opening of uniform width from the bottom to the top, supporting lips located at the lower edges of said flanges, a vending slide located in said opening and having side parts with grooves forming a slideway to conduct a coin from said coin slot, and means for operating the vending slide.
6. A vending machine including a case having a coin slot, a supporting plate located within the case and having depending flanges forming a slide opening of uniform width from bottom to top to receive a vending slide insertible from the top, said plate having cross bars extending between said flanges, a vending slide located within said opening, said vending slide including side parts rising from its lower edge and located in grooves in one of said cross bars and with a cross piece extending between the lower edges of the side parts within said slide opening, said side parts having a slideway to guide a coin from said coin slot to a position in line with an opening in one of said cross bars on said plate, a push rod mounted in and extending through said cross bars and through said cross piece, and a spring located between the cross bar and said cross piece.
7. A vending machine including a case having a coin slot, a supporting plate located within the case and having depending flanges forming a slide opening of uniform width from bottom to top to receive a vending slide insertible from the top, said plate having cross bars extending between said flanges, lips extending from the bottom edges of said flanges toward each other, a vending slide supported upon said lips and having side parts located in grooves in one of said cross bars and rising therefrom and having slideways to guide the movements of a coin from said coin slot, a cross piece extending between said side parts, a push rod mounted in and extending through said cross bars and through said cross piece, and a spring mounted upon said push rod and thrusting against a cross bar and a cross piece.
8. A vending machine including a case having a coin slot, a supporting plate located within the case and having a groove for a vending slide with cross bars extending across said groove, a vending slide located within said groove and having an opening extending in the direction of depth therethrough and with a slideway extending diagonally across said opening to guide the movements of a coin from said coin slot, a cross piece extending across said opening, a push rod extending through said cross bars and cross piece, a spring upon said push rod, and a sleeve surrounding said spring and supported at its opposite ends in said cross bars.
9. A vending machine including a case having a coin slot, a supporting plate located within the case and having a groove for a vending slide with cross bars extending across said groove, a vending slide located within said groove and having an opening extending in the direction of depth therethrough and with a slideway extending diagonally across said opening to guide the movements of a coin from said coin slot, a cross piece extending across said opening, a push rod extending through said cross bars and cross piece, a spring upon said push rod, and a sleeve surrounding said spring and supported at its opposite ends in said cross bars.
10. A vending machine including a case having a coin slot, a vending slide comprising an open sided box with a lipped groove in each side forming a slideway to guide the movements of a coin from said coin slot, a magnet located at one side of the slideway, the latter widening out below the magnet, and means for operating the slide.
11. A vending machine including a case having a coin slot, a vending slide comprising an open sided box with a lipped groove in each side forming a slideway to guide the movements of a coin from said coin slot, a magnet forming a portion of one side of said slideway, the latter widening out below said magnet, and means for operating the slide.
12. A vending machine including a case having a coin slot, a vending slide comprising an open sided box with a lipped groove in each side forming a slideway to guide the movements of a coin from said coin slot, a magnet located at one side of the coin slot, a cap located over the slideway at a point opposite the magnet, and means for operating the vending slide.
13. A vending machine including a case having a coin slot, a vending slide located underneath the coin slot and having a slideway to guide the movements of a coin from said coin slot, a magnet forming a portion of one side of said coin slot, the latter widen-

ing out below said magnet, a cap overlying the slideway opposite said magnet, and means for operating the vending slide.

14. A vending machine including a case 5 having a coin slot, a vending slide spaced from said coin slot and having side parts rising therefrom with a slideway to guide the movements of a coin from said coin slot, a magnet forming a portion of one wall of 10 said slideway, a cap overlying the slideway opposite said magnet, a stop located between said side parts underneath said slideway, and means for operating the vending slide.
15. A vending machine including a case 15 having a coin slot, a vending slide having a slideway to guide the movements of a coin from said coin slot and an opening to receive spurious devices, a trap pivotally suspended across said slideway adjacent to said 20 opening, and means for operating the vending slide.
16. A vending machine including a case 25 having a coin slot, a vending slide having a slideway to guide the movements of a coin from said coin slot and an opening to receive spurious devices, said slide having an opening extending in the direction of depth therethrough, a stop at the front of said 30 opening, a trap pivotally suspended across the slideway back of said stop and adjacent to said opening, and means for operating the vending slide.
17. A vending machine including a case 35 having a coin slot, a vending slide spaced from said coin slot and having a slideway to guide the movements of a coin from said coin slot, a magnet located at one side of said slideway, a cap overlying the slideway opposite said magnet, a trap pivotally suspended 40 across said slideway, and means for operating the vending slide.
18. A vending machine including a case 45 having a coin slot, a vending slide spaced from said coin slot and having an opening with a lipped groove in each wall thereof forming a slideway to guide the movements of a coin from said coin slot, a clearing lever forming a portion of one of the lips of said 50 slideway, means for operating the lever, and means for operating the vending slide.
19. A vending machine including a case 55 having a coin slot, a vending slide having an opening with slots in each side wall thereof forming a lipped groove constituting a slide- 60 way to guide the movements of a coin from said coin slot, a pivotally mounted lever forming a portion of the lip on one side of said slideway, means for moving the lever on its pivot, and means for operating the vending slide.
20. A vending machine including a case 65 having a coin slot, a vending slide containing a slideway to guide the movements of a coin from said coin slot, a lever pivotally mounted on the vending slide and forming a 70 portion of said slideway, means for operating the vending slide, and connections between said operating means and lever for operating the latter.
21. A vending machine including a case 75 having a part with a coin slot therein and a groove in its side walls, a front removably secured to the case and containing a coin tray with flanges projecting into said grooves, and vending mechanism located 80 within the case and including means for delivering a coin from the coin slot to said coin tray.
22. A vending machine comprising a case 85 including a cover having a coin slot therein and a groove in its side walls, a front piece secured in place by said cover and having a tray extending from its back face and underlying said coin slot, said tray having flanges located in said grooves, means for securing the cover in place, and vending mechanism located within the case to guide a coin from said coin slot to said tray.
23. A vending machine comprising a case 90 including a front plate, means for securing the front plate, said case having grooves in its side walls, a cover secured in place by said front plate, a front piece secured in place by said cover, the latter having a coin slot, a coin tray rigidly secured to and projecting 95 from the back face of said front piece and having flanges located in said grooves, and vending mechanism within the case to conduct a coin from said coin slot to said tray.
24. A vending machine including a box, a 100 base slidably mounted therein and having cross bars with an opening therebetween, a slide movably mounted on the base and including cross pieces and side pieces with an opening between said side pieces within 105 which opening one of the cross bars is located, a push rod slidably within said cross bars of the base and a cross piece of the supporting slide, a spring mounted upon the push rod within the inclosure formed between said cross bar on the base and a cross 110 piece on the slide, and an ejector secured to the slide.
25. A vending machine including a box, a 115 base therein having cross bars with an opening therebetween, a supporting slide mounted on the base and including cross pieces and side pieces with an opening between said side pieces within 120 which opening one of the cross pieces of said supporting slide is located, a push rod slidably mounted within said cross bars and a cross piece on the base and supporting slide, a spring mounted upon the push rod within the inclosure formed between a cross bar on the base and a cross 125 piece on the slide, and an ejector secured to the slide.
26. A vending machine including a box, a 130 base therein having cross bars with an opening therebetween, a supporting slide mov-

ably mounted on the base and including a cross piece and side pieces, the latter spaced apart to provide an opening therebetween, one of said cross pieces extending across said opening, a push rod slideable within the cross bars of the base and cross pieces of the supporting slide, a pin extending through the push rod and adapted to rest against

said cross piece, a spring mounted upon the push rod and pressing against said pin and 10 against one of said cross bars, and an ejector secured to the slide.

HARRY H. GOLDSTEIN.
